CLARENCE L. PARKER, OF LOS ANGELES, CALIFORNIA.

DEEP-WELL OUTFIT.

1,149,677.

Specification of Letters Patent. Patented Aug. 10, 1915.

Application filed June 13, 1912. Serial No. 703,537.

To all whom it may concern:

Be it known that I, CLARENCE L. PARKER, a citizen of the United States, residing at Los Angeles, in the county of Los Angeles and State of California, have invented a new and useful Deep-Well Outfit, of which the following is a specification:

This invention has reference to improvements in deep well outfits, and its object is 10 to provide a means which may be installed in the derrick over a well for suspending sections of the sucker rod, and its object is to provide means whereby the rods may be kept straight while out of the well and in 15 position for ready handling whether being removed from the well or placed therein.

Sucker rod sections are of comparatively short length and the lengths are united by couplings, so that in a deep well, such as an 20 oil well, many sucker rod sections are united end to end, for the pump cylinder is lodged deep in the well. It is sometimes necessary to remove the pump piston or even the pump cylinder and for such purpose the sucker rod 25 cylinder must also be removed. The usual custom as heretofore practised has been to drag the rod sections out of the derrick as they are removed from the well and lay them lengthwise one on the other. The sucker rods may 30 be uncoupled at alternate or more distant couplings or even at each coupling, and there is great liability of the couplings becoming wedged in between the rods in the hoisting and the rod sections are thereby 35 easily bent or kinked. Such a bent rod is not only difficult to couple to the remainder of the rod when being replaced in the well, but a straight sucker rod will wear longer than a crooked one and will also cause less 40 wear on the tube, besides offering less resistance. All these features count in both time and labor, and, therefore, in money saved.

In accordance with the present invention 45 the hanger device is suspended from the top of the derrick into the interior thereof for an appropriate distance, and this hanger device contains a number of sockets or receptacles for the corresponding ends of the 50 sucker rod sections, so that on the removal of a sucker rod from the well each section or group of sections removed may be lifted into the hanger device in order to there remain without liability of damage and also 55 out of the way until again wanted. By

providing the hanger device with a suitable number of receptacles or seats for the rod sections, the entire sucker rod may be accommodated and when again wanted the sections are in convenient reach of the operator to be readily screwed one after the other in order on to the portion of the sucker rod already being inserted into the well tubing without liability of bending or kinking, and consequently the rod may be 65 maintained straight and in the most effective working condition, even though repeatedly removed from the well and replaced therein.

The invention will be best understood 70 from a consideration of the following detailed description, taken in connection with the accompanying drawings forming a part of this specification, with the further understanding that while in the drawings different embodiments of the invention are 75 illustrated, the invention is susceptible of other practical embodiments, wherefore it is not confined to any strict conformity with the showing of the drawings, but may be 80 changed and modified within such limits as do not mark any material departure from the scope of the invention.

In the drawings: Figure 1 is a vertical section through a well derrick showing the 85 invention applied. Fig. 2 is a vertical section through the portion of the hanger designed to directly receive the ends of the sucker rod sections and drawn to a larger scale than Fig. 1. Fig. 3 is a section on 90 the line 3-3 of Fig. 2 and showing some sucker rod sections in place. Fig. 4 is a vertical section through another form of sustaining device for the sucker rod sections. Fig. 5 is a fragmentary plan view of the 95 structure shown in Fig. 4.

Referring to the drawings there is indicated in Fig. 1 a derrick 1, such as is used in connection with deep wells, particularly oil wells, but no attempt is made to show the 100 derrick in any particular detail, since the special structure of the derrick does not enter into the present invention. The derrick is shown as associated with a well casing 2, that end only of the casing projecting above the ground being indicated, and here again no attempt is made at a showing of special structure.

The derrick is indicated as provided with crown blocks 3, rope sheave 4, tubing line 5

and bull wheel 6, while the well casing 2 is shown as provided with a casing head 7 and inner tubing 8. The tubing rope carries a hook 9 sustaining an elevator 10 for a sucker rod made up of sections 11, and these sucker rod sections terminate in screw ends 12 which, when the sucker rods are joined together, are united by couplings 13.

The structure so far described may follow the usual practice in deep well outfits so far as the present invention is concerned, and, therefore, needs no particular detailed description.

Adapted to the derrick is a hanger rod 14 or more than one such rod in accordance with the particular construction employed, and each rod 14 has one end formed into a hook 15 adapted to engage over one of the crown blocks 3 in such manner that the rod or rods will hang pendently therefrom. The derricks are customarily of considerable height, which height is much more extensive than the length of a sucker rod section and may be greater than two sucker rod sections joined together.

Sustained by the lower ends of the hanger rods 14 when two such rods are employed is an elongated receiver frame 16 in the form shown in Figs. 1, 2 and 3, and best shown in Figs. 2 and 3. This frame, which may be in the form of a single casting, has enlargements 17 at the ends each with a passage therethrough for a respective one of the hanger rods 14, which latter at their lower ends are threaded, as indicated at 18, for the reception of a nut 19, and this nut may be held against accidental displacement by a cotter pin 20 passed through the threaded portion of the rod or by any other suitable means, although a cotter pin is to be preferred because of its simplicity. The frame 16 between the enlargements 17 is in the form of a web 21 and projecting from this web are a number of fingers 22, each of which may be laterally expanded on the upper edge, as shown at 23, and may also rise slightly toward the ends remote from the web 21 with relation to the normal position of the frame 16 when mounted on the suspension rods 14. The free end of each finger 22 may be arranged at a slightly rising angle with relation to the rest of the finger, as indicated at 24.

The space between any two adjacent fingers 22 is such that a sucker rod 11 may be introduced between the fingers, but the sucker rods are customarily enlarged at their screw threaded ends and are also provided with tool receiving portions. The space between adjacent fingers 22 is so related to the enlarged ends of the sucker rods that such enlarged portions will engage the fingers while the main portion of the sucker rod section is between such fingers, wherefore the sucker rod section is sustained by the en-

larged portion, while the main portion of the rod is in pendent relation to the fingers upholding it.

By properly positioning the frame 16 with relation to the tubing rope 5 the sucker rod sections as they are withdrawn from the well tubing 8 may be elevated to a suitable height and then unscrewed from the portion of the sucker rod still within the well and then elevated to one side sufficiently to engage between appropriate fingers 22, when the rod may be slightly lowered until the enlarged end of the portion of the sucker rod engaging between the fingers rests on said fingers. The sucker rod sections are or may be all of approximately the same length and the frame 16 may be sufficiently extensive to receive all the rod sections which are needed for a well. In this way the sucker rod sections as removed from the well are hung pendently from their then upper ends sufficiently to one side to be out of the way but still in such relation to the well that they may be readily applied when the sucker rod is being inserted into the well. By this means all liability of bending or kinking the sucker rod is avoided, and consequently the rod is at all times straight, the sections may be readily screwed together as needed, and wear and friction due to bending or kinking of the rod sections is wholly avoided.

Instead of having a straight supporting frame as in Figs. 1, 2 and 3, a circular frame may be employed, in which case but one suspension rod 14 is employed. There is then provided a spider support comprising a hub 25 suitably bored to receive the suspension rod 14, which, like the structure shown in Figs. 1, 2 and 3, is provided with a nut 19 to be applied to its threaded end 18 and a cotter pin 20 is used to hold the nut in place. The hub carries a radially disposed plate 26 slightly dished toward the hub, and this plate is formed with a circular series of entering slots 27 extending from the periphery to near the hub. Intermediate of the slots 27 are other entering radial slots 28 extending from the periphery toward the hub, but to a less extent than the slots 27, while between the slots 27 and 28 are radially entering slots 29 commencing at the periphery and extending toward the hub to a still less distance. The number of slots and their disposition depends upon the diameter of the supporting plate 26, and as these slots are of the same width which may be equal to the width between two fingers 22 of the form shown in Figs. 1, 2 and 3, their extent toward the hub is limited by the approach of the slots and the necessity of having the plate of requisite strength to withstand the strain of the weight of the sucker rods. To strengthen the plate it is provided on the under side with webs 30. The slots

27, 28 and 29 define fingers 31 between them and each finger has a short upturned end 32 serving in conjunction with the dished form of the plate to prevent accidental escape of 5 any of the sucker rod sections which may be lodged in the slots 27, 28 or 29. Those portions of the plate 26 defined by the slots 27, 28 and 29 are also in effect fingers, between which the sucker rod sections are inserted 10 the same as in the form shown in Figs. 2 and 3. The capacity of the plate 26 may be quite large due to the numerous slots, some of which need only be long enough to accommodate one sucker rod section, and the 15 others may be long enough to accommodate several sucker rod sections each. One advantage of the plate form of support for the sucker rods is that it may be rotated upon the suspension rod 9 as an axis and any of 20 the rods carried by the rotatable plate may be brought adjacent the well tubing so as to require but a minimum of movement to bring the rod into position to enter the well, or on being removed therefrom to enter an 25 appropriate slot in the plate. The rotatable carrier for the sucker rods illustrated in Figs. 4 and 5 is also more compact than the type shown in Figs. 2 and 3.

The suspension rod 14 with its engaging 30 hook 15 designed to engage over a crown block 3 may be readily applied to existing forms of derricks without interference therewith and without the necessity of any change in the structure of the derrick even 35 to the extent of boring bolt holes, and when the suspension device is not in use it may be readily removed and placed out of the way at some point of storage. Of course, other forms of suspension, for the supporting 40 frame, than the rod 14 with the hook end 15 may be used. By providing slots of varying lengths in the circular frame form of the device the rods occupy but a minimum of space and therefore offer no unnecessary obstruction for the tubing elevator to catch on 45 and do damage. Furthermore, the frame will accommodate more rod sections and may therefore be of less diameter and interfere less with the tools used about the well 50 than if the slots were all of the same length.

When the rod sections are being placed in or taken from the well, a workman stands in the derrick near the rod supporting frame and pulls the hoisted rod over into the frame 55 when the rod is lowered until seated, after which the elevator is disconnected and lowered from the next rod section. For placing the rod sections in the well the operation is reversed.

60 What is claimed is:—

1. The combination with a well derrick having a crown block and pulley at the top, a bull wheel at the bottom, and a hoisting

cable leading from the bull wheel over the said pulley and down into the well, a hanger 65 rod formed at its upper end with a hook to be engaged with the crown block and extending downwardly within the derrick, a frame rotatably mounted on the lower end of the rod, said frame being located at one 70 side of the center of the derrick and at an intermediate point of the cable and having seats which open inwardly toward the cable, said seats being adapted to receive the sucker rod sections, whereby the seats of the 75 frame may be successively brought into juxtaposition to the hoisting cable so as to permit the ends of the sucker rod sections to be carried into the seats, causing said sections to be suspended from the frame with 80 their lower ends free of any support.

2. The combination with a well derrick having a crown block and pulley at the top, a bull wheel at the bottom and a hoisting 85 cable leading from the bull wheel over said pulley down into the well, a hanger rod formed at its upper end to rigidly engage with the crown block and extending downwardly within the derrick, a frame mounted on the lower end of the rod and located at 90 one side of the center of the derrick at an intermediate point of the cable, said frame having seats which are freely open inwardly, said seats being located in juxtaposition to the hoisting cable and adapted to receive 95 the sucker rod sections directly from said cable, said frame being arranged above the bottom of the derrick at a sufficient distance so that when the sucker rod sections are carried into the seats from the hoisting cable, 100 they are suspended from their upper ends with their lower ends free.

3. The combination with a well derrick, of a suspension member for sucker-rod sections sustained from the top of the derrick 105 in elevated relation to the bottom portion of the derrick and also to one side of the center line of the well, said suspension member having open seats for suspending sucker-rod sections by their upper ends, said seats 110 being open toward the middle portion of the derrick to receive the sucker-rod sections directly from the hoisting cable as they are lifted from the well and to present them for insertion into the well, the elevation of the 115 suspension member being such that the lower ends of the suspended sucker rod sections are free from support.

In testimony that I claim the foregoing as my own, I have hereto affixed my signature in the presence of two witnesses.
